UNITED STATES PATENT OFFICE.

FRED B. SMALL AND JAMES C. MULLIGAN, OF BATH, MAINE.

DETACHABLE SUPPORT FOR IMPLEMENTS AND OTHER ARTICLES ON STOVES.

No. 826,373.

Specification of Letters Patent.

Patented July 17, 1906.

Application filed April 26, 1905. Serial No. 257,481.

To all whom it may concern:

Be it known that we, FRED B. SMALL and JAMES C. MULLIGAN, citizens of the United States, and residents of Bath, in the county 5 of Sagadahoc and State of Maine, have invented a new and Improved Detachable Support for Implements and other Articles on Stoves, of which the following is a full, clear, and exact description.

10 The object of this invention is to provide a novel simple device and means for detachably clamping it upon the border-flange of a top plate on a stove or range, the improvement affording very convenient means for 15 holding necessary implements used at a stove for ready removal as may be desired.

The invention also embodies convenient means for supporting plates or other dishes adjacent to or over the stove to warm them, 20 and, furthermore, provides an extensible support for towels and the like near to or above the stove or range to dry them.

25 The invention consists in the novel construction and combination of parts, as is hereinafter described, and defined in the subjoined claims.

30 Reference is to be had to the accompanying drawings, forming a part of this specification, in which similar characters of reference indicate corresponding parts in all the figures.

Figure 1 is a vertical section of the improvement secured in position on a stove or range, shown in part. Fig. 2 is a vertical section of 35 portions of a towel-support that is a detail of the invention. Fig. 3 is an enlarged side view of a novel connection between two tubular members for a towel-support that are details of the invention, and Fig. 4 is a 40 partly-sectional side view of a dish-supporting bracket-plate and a fragmentary side view of a supporting means therefor.

45 While the improvement may be connected with a wall or other stable object for its support in position for use, it is particularly well adapted for removable attachment upon the edge portion of the top plate on a range or stove and is shown as connected with such a support in a manner that permits its convenient service and removal when this is desired.

50 The device comprises a plurality of tubular sections, (three being represented in Fig. 1 and respectively designated by the characters 6, 7, and 8,) said tubular sections having such relative diameters as permits the tube-section 7 to slide freely within the section 6 and the section 8 to slide within the tube-section

7. The normally lower end of the tube-section 8 is loosely connected with the upper end of the tube-section 7 by the means clearly shown in Fig. 3, constructed as follows: A 60 gimbal-ring a is loosely mounted upon the normally lower portion of the tube-section 8 and is thereon held by a collar a' , which is secured upon the end of the same. A short sleeve a^2 is secured upon the upper end of the 65 tube-section 7 and encircles it, and from the upper edge of the sleeve project two ears a^3 , said ears being diametrically opposite each other. The ears a^3 are sufficiently spaced apart to permit them to loosely embrace the 70 gimbal-ring whereon they are pivoted by studs a^4 , that project oppositely from the ring and through a perforation in each ear, respectively. It will be seen that if the tube-section 8 is drawn upward in the tube-section 75 7 until the collar a' impinge upon the gimbal-ring a the section 8 may be rocked downward into a horizontal position and be supported by the contact of the collar against the inner side of the tube-section 7 and the 80 seated engagement of the tube-section 8 with the top edge of the sleeve a^2 at a point opposite from the point of contact just mentioned, this rocked adjustment of the tube-section 8 being clearly shown in Fig. 2. In the tube-section 8 a rod-like arm 9 is inserted and adapted for reciprocation, there being enlargements b b' on the respective ends of the arm that prevent its removal, as will be 85 further explained. As shown in Fig. 2, the 90 bore of the tube-section 8 is reduced in diameter at and near its normally upper end, affording an internal shoulder b^2 , whereon the headed enlargement b' contacts when the arm is drawn outward its full extent, thus 95 preventing its removal from the tube-section 8. A spring latch-bar 10 is secured by one 100 end on the exterior of the tube-section 6 and at its upper end is furnished with a nose 10^a , that is adapted by resilience of the latch-body to enter an opening in the wall of said tube-section and project therethrough a short distance, and, as shown in Fig. 1, there is a finger-hold 10^b formed on the latch-bar near the nose and inclined outward for 105 convenient manipulation. A looped guard-piece 10^c is secured on the tube-section 6, which loosely embraces the latch-bar 10 and prevents its lateral displacement. It will be seen that if the tube-section 6 is supported in 110 a vertical position the telescoping sections 7 and 8 along with the arm 9 may all be slid

together and housed in the outermost tube-section, as appears in Fig. 1. It will also be evident that if the tube-section 7 is drawn outward until its lower end passes the nose 5 of the spring latch-bar 10 the resilience of said latch-bar will automatically engage said nose with the lower end of the tube-section 7, and thus support it along with the section 8 and arm 9 in an elevated position, whereupon these parts 8 and 9 may be drawn out successively and rocked into a horizontal position, as hereinbefore explained.

A preferred means for supporting the extensible tube-sections hereinbefore described 15 in an upright position at a stove or range for the purpose of drying towels or other pieces of fibrous fabric near such a heating device on the horizontally-disposed members thereof is shown in Fig. 1 embodying the following 20 details: A bracket-plate 11, having an upright socket 11^a at one end and an upright flange 11^b at the opposite end, receives the lower end of the tube-section 6 in the socket 11^a, wherein said section is secured, this connection serving to project the bracket-plate and flange laterally from the tube-section. An upright flat post 11^c, having an upturned hook member 11^d formed on the lower end thereof, is longitudinally slotted, as shown at 25 11^e. The hook member 11^d is designed for a clamped connection with the border-flange A' on the top plate A of a stove or range, and to this end a set-screw d is screwed through one side of the hook member 11^d against the border-flange after the hook member is hooked thereon, as shown in Fig. 1, this connection disposing the post 11^c vertically. On a foot 11^e hanger-arms 11^g are formed or secured. Through the upper portion of the 30 40 foot-plate 11^e a transverse perforation is formed for reception of the threaded shank 11^h of another hanger-arm 11ⁱ, similar to the arms 11^g and having a collard thereon, which seats upon the outer surface of the foot-plate 45 when the threaded shank is passed through the perforation therein. In the flange 11^b a perforation is formed near its upper end that permits the threaded shank 11^h to be passed therethrough after it has been inserted 50 through the longitudinal slot c, and on the thread of said shank a winged nut d' is screwed, which by adjustment clamps the foot-plate and post upon the flange 11^b, whereby the tubular standard 6 and the telescoped extensions 7, 8, and 9 are supported vertically on the stove-plate A. The arms 11^g and 11ⁱ are bent to form concavities in their upper sides near the free ends, thus adapting them for holding stove furniture, 55 such as a stove-lid lifter, a poker, and a shovel, which will hang adjacent to the stove-body for use as may be desired. The provision of the longitudinal slot c in the post 11^c permits the bracket-plate and 60 holder-arms to be raised or lowered some- 65

what from or toward the stove-plate A, as may be desired, and obviously the clamping device may be engaged with the border-flange on any side edge of the plate A. On the exterior of the tube-section 6 at its upper 70 end a coniform collar e is formed or secured, this upwardly-tapered collar affording support for a conforming base-ring e', whereon the lower ends of a plurality of spaced arms e² are secured. The arms e² incline outward 75 somewhat and at their upper ends are secured upon a plate-metal dish-holder 12, which is preferably circular and centrally perforated for the transmission of heat therethrough. It will be seen in Fig. 1 that the 80 dish-holder will receive and support plates or other dishes near the stove or above it near the vertical plane of the border-flange A', so that cold dishes may be warmed. Furthermore, cooked vegetables or meat that have 85 been placed in dishes may be kept warm by seating such dishes upon the holder-plate 12. A dish-holder 12^a may be rigidly connected with a single arm e³, as shown in Fig. 4, and thus be held at one side of the telescoping 90 members of the tubular standard already described, and it will be obvious that a plurality of plate-like dish-holders 12^a may be mounted on the standard 6 and secured on the arms e³, which project upward and outward from a base-ring e', thus affording 95 means for the support of different dishes above the stove at the same time.

It is contemplated to coat the details of the improvement with any suitable wash or 100 plating for its ornamentation and preservation from rust.

It is claimed for this device that it embodies three valuable features in concrete form—viz., a rack for holding towels and 105 dish-cloths near the stove for drying purposes, a dish-holder to warm or keep warm dishes or cooked food, and a hanger for support of stove utensils in convenient position for removal and use. 110

Minor changes in constructive details may be resorted to without departure from the spirit and scope of our invention, and we claim the right to deviate from the exact forms shown within the scope of the claims. 115

Having thus described our invention, we claim as new and desire to secure by Letters Patent—

1. A support for articles comprising two telescoping members, one adapted to be 120 flexed at an angle with respect to the other, and said latter portion consisting of telescoping members, whereby said portion may be extended.

2. A support for articles comprising two 125 telescoping members, one adapted to be flexed at an angle with respect to the other, each of said portions consisting of telescopic members, whereby either of said portions may be extended. 130

3. A support for articles, embodying a standard having a plurality of telescoping tubular members, one member having a swiveling and hinged connection with a member it slides within, said connection consisting of a gimbal-ring loosely mounted upon the slideable member, a fixed collar on the end of said member, and opposite ears on the receiving tubular member, said ears being pivoted upon the ring.

4. A support for articles, embodying a standard having a plurality of telescoping members, means for supporting the standard upright, a swiveling and hinged connection

for holding two upper extensible members 15 flexed at a right angle on the remaining upright members, and a latching device adapted for supporting certain of the telescoping members elevated within the outer member of the standard.

In testimony whereof we have signed our names to this specification in the presence of two subscribing witnesses.

FRED B. SMALL.
JAMES C. MULLIGAN.
